UNITED STATES PATENT OFFICE

154,776

DESIGN FOR A HAND TRUCK ATTACHMENT OR SIMILAR ARTICLE

Benjamin Hooz and Samuel T. Mello,
Los Angeles, Calif.

Application February 15, 1947, Serial No. 136,928

Term of patent 14 years

(Cl. D14—3)

To all whom it may concern:

Be it known that we, Benjamin Hooz, a citizen of the United States, residing in Los Angeles, in the county of Los Angeles, State of California, and Samuel T. Mello, a citizen of the United States, residing in Bell Gardens, city of Los Angeles, county of Los Angeles, State of California, have invented a new, original, and ornamental Design for a Hand Truck Attachment or Similar Article, of which the following is a specification, reference being had to the accompanying drawing, forming a part thereof.

Figure 1 is a rear perspective view of a hand truck attachment, showing our new design.

Figure 2 is a side elevational view as the attachment would appear in one position.

Figure 3 is a side elevational view as the attachment would appear in another position.

Figure 4 is a side elevational view as the at-

tachment would appear in still another position.

The dot-and-dash line showing of the hand truck in the several drawing figures is for illustrative purposes only.

We claim:

The ornamental design for a hand truck attachment or similar article, substantially as shown and described.

BENJAMIN HOOZ.
SAMUEL T. MELLO.
